UNITED STATES PATENT OFFICE

2,477,109

SPINDLE FOR SUPPORTING WORK
ENGAGING STRIPS

Otto K. Ziebur, New London, Wis.

Application April 18, 1947, Serial No. 742,406

3 Claims. (Cl. 51—194)

1

This invention relates to a spindle primarily adapted for supporting an elongated strip of abrasive material but which is likewise well adapted for supporting strips of other material for use in buffing and polishing or similar operations and to which a compound for such operations may be added.

More particularly, it is an object of the present invention to provide an improved construction of supporting spindle having means for effectively mounting an elongated work engaging strip thereon so that it can be readily applied to or removed from the spindle and so that it will be supported spirally wound around the spindle and with the convolutions thereof in engagement.

More particularly, it is an object of the present invention to provide novel strip retaining means for a spindle by means of which a strip, such as an abrasive strip may be effectively secured spirally wound thereon and without the use of an adhesive or other securing mediums and so that the strip may be quickly and easily removed and replaced.

Various other objects and advantages of the invention will hereinafter become more fully apparent from the following description of the drawing, illustrating preferred embodiments thereof, and wherein:

Figure 1 is a plan view of one embodiment of the spindle shown with an abrasive strip spirally wound and secured thereon;

Figure 2 is a view similar to Figure 1 but showing the spindle at right angles to its position of Figure 1 and with the abrasive strip and retaining collar thereof removed;

Figure 3 is an enlarged longitudinal sectional view, partly in elevation showing the spindle assembled and with an abrasive strip thereon;

Figure 4 is a cross sectional view of the assembled spindle taken substantially along a plane as indicated by the line 4—4 of Figure 3;

Figure 5 is a fragmentary plan view of the abrasive strip;

Figure 6 is an end elevational view of another embodiment of the abrasive spindle, and

Figure 7 is an enlarged fragmentary side elevational view, partly in section of the outer end of the spindle of Figure 6.

Referring more specifically to the drawing, the invention will be described in conjunction with its use for mounting a strip of abrasive material but it will be readily apparent as the description proceeds that strips of other material and for other uses such as cloth used for polishing or buffing could readily be mounted on the spindle

2

in the same manner and for the same purpose as the abrasive strip.

Referring particularly to Figures 1 to 5, in the embodiment of the invention as disclosed therein the improved spindle, designated generally 8 and comprising the invention includes an elongated outer end portion or stem 9 and an opposite end portion or shank 10. The adjacent ends of the stem 9 and shank 10 are integrally joined by a frusto-conical neck 11 which is tapered in a direction toward the shank 10 and which forms an annular shoulder 12 at its junction therewith and which faces toward the stem 9. The enlarged end of the neck 11 merges with the periphery of the stem 9 which, like the shank 10 is circular in cross section.

The stem 9 at its opposite, outer end is provided with a slot 13 which extends transversely therethrough and which opens outwardly of the outer end thereof. The slot 13 may be inclined with respect to the axis of the spindle 8, as illustrated in Figure 3, if desired. Said last mentioned end of the stem 9 is provided with a substantially radially disposed internally threaded bore 14, extending from the periphery thereof and opening into the slot 13 for receiving a set screw 15, for a purpose which will hereinafter become apparent.

An externally knurled collar 16 is removably disposed on the shank 10 and is provided with a bore 17 which tapers from end-to-end thereof and with the largest end of the bore disposed at the inner end of the collar or adjacent the stem 9.

As best illustrated in Figure 5, an elongated strip 18 of abrasive material is adapted to be wound spirally about the stem 9, as best seen in Figure 1 and with convolutions thereof preferably in engagement. The strip 18 is provided with a reduced end 19 formed by cutting one longitudinal edge thereof off at an angle, as seen in Figure 5, and said end 19 is adapted to be inserted transversely into the slot 13 and is secured therein by tightening the set screw 15. The strip 18 is then wound in either direction spirally about the stem 9 and so that its abrasive side will be outermost. The strip 18 is provided with an opposite tapered end 20 formed by cutting its other longitudinal edge at an angle, as seen in Figure 5, and said strip is of such a length that when wound as seen in Figure 1 on the stem 9 said tapered end 20 will be disposed in engagement with the frusto-conical neck 11. After thus winding the strip 18 on the stem 9 the retaining collar 16 is applied and engaged over the end portion 20 of the strip by advancing the collar

50

55

toward the stem 9 while rotating it in the same direction that the strip 18 is wound. In order to provide a secure connection against slippage for said last mentioned end of the abrasive strip 18, the stem 9 adjacent the neck 11 is provided with a roughened or serrated annular portion 21 to afford a frictional engagement with the inner side of the strip 18 and the serrated external surface of the strip will provide a good frictional engagement with the retaining ring 16 and will roughen and serrate the enlarged end of the bore 17 thereof so that a secure connection will be provided and which will only be released upon rotation of the retaining collar 16 in the opposite direction and while drawing said collar outwardly of the shank 10.

Obviously, if the abrasive strip 18 is of sufficient thickness its end 19 will be retained in the slot 13 without the use of the set screw 15 which, however, will afford additional securing means and is essential for relatively thin abrasive strips.

Figures 6 and 7 illustrate a slightly modified form of spindle 8a which differs from the spindle 8 only in respect to the outer end of the stem 9a thereof. The outer end of the stem 9a is provided with a restricted neck 22 of circular cross section on which a sleeve or collar 23 is turnably mounted and retained in applied position thereon by the rolled or enlarged outer end 24 of said neck 22. The slot 13a of the stem 9a and which corresponds to the slot 13, is formed in the neck 22 thereof and opens outwardly of the enlarged end of said neck and extends transversely therethrough. The sleeve 23 is provided with complementary longitudinally extending slots 25 which open outwardly of the outer end thereof, as seen in Figure 6, and which extend inwardly substantially to the depth of the slot 13a. As seen in Figure 6, the sleeve 23 may be rotated to position both of the slots 25 in registry with the slot 13a and when so disposed, the end 19 of the abrasive strip 18 can be inserted transversely through one of said slots 25 into the slot 13a. The strip 18 is then wound in the same manner as previously described, and it will be readily apparent that the initial convolution of the strip 18 will engage partially around the sleeve 23 and will cause said sleeve to be rotated on the neck 22, in the direction that the strip 18 is wound, so that one edge of the slot 25, through which the strip extends, as seen in Figure 6, will be moved into a position to clamp a portion of the strip end 19 between said edge and an adjacent edge of the slot 13a to thereby securely clamp the ends 19 in the slot 13a and without the use of a set screw or other means. The opposite end 20 of the strip 18 is secured in the same manner as previously described and as best illustrated in Figure 3.

Various other modifications and changes are likewise contemplated and may obviously be re-

sorted to, without departing from the spirit or scope of the invention as hereinafter defined by the appended claims.

I claim as my invention:

1. A spindle for mounting a flexible abrasive strip or the like having a stem on which an abrasive strip is adapted to be spirally wound, said stem being provided with a restricted neck adjacent one end thereof provided with a slot extending transversely therethrough, a sleeve turnably disposed on said neck and provided with circumferentially spaced slots arranged for movement simultaneously into or out of alignment with said first mentioned slot and through one of which last mentioned slots an end of the strip is adapted to extend into the first mentioned slot, said strip being wound around said sleeve for causing the sleeve to rotate on the neck for moving the slots thereof out of complete registry with the slot of said neck for clamping said strip end in the first mentioned slot.

2. A spindle for mounting a flexible abrasive strip or the like comprising a stem portion on which an abrasive strip is adapted to be spirally wound, said stem having a restricted neck portion provided with a transversely disposed slot, a sleeve rotatably mounted on said neck and having a slot for registry with the first mentioned slot, said slots being adapted to be disposed in alignment for receiving an end of the strip and said strip, being wound about said sleeve for rotating the sleeve on the neck portion for moving the slots out of registry for clamping said end therein.

3. A spindle for mounting a flexible abrasive strip or the like, comprising a portion on which an abrasive strip is adapted to be spirally wound, said portion being provided with a transversely disposed slot, a sleeve rotatably mounted on said slotted portion and having a slot for registry with the first-mentioned slot and adapted to be disposed in alignment therewith for receiving an end of the abrasive strip, said strip being wound about said sleeve for applying a torsional pressure thereto for moving the slot out of registry for clamping the aforementioned end of the abrasive strip therein.
